UNITED STATES PATENT OFFICE.

WALTER MORTON, OF WINDSOR, ONTARIO, CANADA.

CARBURETOR.

Application filed July 11, 1921. Serial No. 483,699.

This invention relates to charge forming devices and more particularly to carburetors for internal combustion engines.

It is an object of the invention to provide a device which will successfully handle present day low grade fuels and which require a better breaking up or finer division, thus permitting a closer and freer combination with air at the time of atomization to form highly combustible charges which will produce even flame propagation and consequent even pressure upon the engine piston, eliminating to a great extent knocks produced by irregular combustion.

15 The invention consists in supplying the ingoing air with the necessary quantity of fuel for low engine speeds and in preparing the fuel for thorough combination with the ingoing air so that it will be carried into the engine in complete combustible form at all engine speeds.

20 The invention also consists in providing improved and efficient means for controlling the mixture by admitting air into the fuel passage prior to atomization and regulating this air inlet.

25 Further, the invention consists in novel means for increasing the air velocity through the restricted portions of a venturi into which fuel is introduced to provide easy starting.

With the foregoing and other ends in view, the invention consists in certain other new and useful features in the construction, arrangement and combination of parts, all as hereinafter more fully described, reference being had to the accompanying drawing in which—

30 Figure 1 is a transverse vertical section through a device illustrative of the invention;

Fig. 2 is a horizontal section of the same substantially upon the line X—X of Fig. 1;

Fig. 3 is a sectional detail of the upper portion of a venturi;

Fig. 4 is a detail of the member shown in Fig. 3 and in end elevation, and

Fig. 5 is a sectional detail of a lower Venturi member.

50 The carburetor shown in the accompanying drawing and illustrative of the invention, comprises the usual and common float chamber 1 containing a suitable float 2 with any suitable means operated by the float for controlling the admission of fuel to the chamber. From the float chamber the fuel

flows through a passage 3 into the bottom of a suitable chamber or well 4 formed in the body of the carburetor between the chamber 1 and the main air passage 5 in the body which extends upwardly through an extension 6 of the body, which extension is adapted to be connected to the lower end of an engine intake manifold (not shown).

Within the lower end of the well 4 is a suitable opening 7 which, during engine operation, controls the flow of fuel from the float chamber into the well and extending downward within the well from the upper end thereof is a tube 8 with its lower end adjacent to and spaced from the jet opening 7. A small air inlet opening 9 is provided at the upper end of the well 4 to admit air into this well, and if found desirable, this air inlet 9 may be provided with any suitable means (not shown) for controlling the size of the inlet or it may be made of a fixed size to be determined upon when the carburetor is built.

From the upper end of the tube 8, a passage 10 extends laterally within the body and opens into an annular passage or chamber 20 formed in a Venturi body, which venturi is indicated as a whole at 12, said venturi comprising an upper member 13, shown in Figs. 3 and 4, and a lower member 14, shown in Fig. 5. These members are set within the bore of the extension 6 of the body and together form a Venturi restriction within the main air passage leading to the engine. The lower member is formed with an annular outwardly extending flange 15 adapted to seat upon a shoulder of the bore and hold the venturi securely in place therein. This member 14 is also formed with an upwardly extending annular rib 16 which co-operates with the lower end surface of the member 13 to form a narrow annular outlet slot 17 opening into the air passage through the venturi at the most restricted part of the venturi. This annular slot is very narrow, preferably about twelve thousandths of an inch and the outer angle or shoulder 18 of the rib 16 co-operates with a downwardly extending flange 19 on the member 13 to form a very narrow annular

55 passage, vertically disposed and communicating with the opening 17. At the outer side of the flange 19 and between it and the body of the carburetor is formed an annular chamber or passage 20 which surrounds the flange 19 and consequently extends around

the venturi opposite the outlet or discharge slot 17. This chamber 20 communicates with the discharge slot through a series of notches 19^a formed in the lower edge of the 5 flange 19, as shown in Fig. 3. With this arrangement a very narrow annular outlet opening for the fuel is provided in the restricted portion of the venturi and this outlet is in communication with the annular 10 chamber surrounding the venturi, through a restricted and tortuous passage at the outlet of which the fuel is taken up by the in-rushing air. The fuel will lose its inertia in large degree during flow to the outlet 15 through the tortuous and restricted passage because of such restriction and upon passing from the outlet into the ingoing air stream, it will be finely divided and picked up by the current of air moving at high velocity 20 through the Venturi tube, as distinguished from entering the air stream under pressure and with velocity, and therefore to a greater or lesser extent, in the form of a solid stream.

25 At the side of the venturi opposite that at which the passage 10 is located, is an outlet 21 controlled in any suitable manner as by an adjustable needle valve 22, and this outlet communicates with a small vertical 30 passage 23 formed in the extension 6 and extending upward past the throttle valve 24 which is located in the bore of this extension. A small outlet passage 25 leads from the passage 23 into the main passage or bore 35 of the extension 6 just above or beyond the throttle valve and thus an idling passage is provided communicating with the chamber 20 and extending past the venturi and the throttle valve so that when the engine is 40 idling and the throttle is closed, as shown in Fig. 1, just sufficient fuel will be drawn through this passage to keep the engine running.

45 As fuel is drawn through the idling passage, the chamber 20 is supplied with fuel from the tube 8 within the well 4 and therefore a quantity of fuel is maintained within the chamber 20 adjacent the main or annular outlet slot 17 so that upon the 50 opening of the throttle, fuel will be at once available for the main annular discharge, the direction of flow from the chamber being simply changed from out through the idling passage to the main annular outlet. 55 Fuel will therefore be supplied through the main outlet of the venturi immediately upon opening of the throttle and the engine will therefore have a quick pick up. To prevent too much fuel being drawn through the 60 idling passage when the throttle is closed, this passage is controlled by the needle valve 22 which may be adjusted to vary the flow. 65 It will be noted that the normal fuel level in the float chamber and consequently in the well 4, is considerably below the annular

main outlet opening 17. This arrangement is provided to prevent flooding through the main outlet opening during idling and at low engine speeds. At high engine speeds or upon increase of speed, the fuel will be 70 gradually drawn from the well 4 through the tube 8 until the well is emptied. When the well is empty, air will be drawn in through the tube 8 from the well along with the fuel supplied through the orifice 7. 75 The amount of fuel at high engine speeds is therefore cut down and regulated by the admission of air along with the fuel prior to the discharge of fuel through the main annular discharge or outlet 17. 80

It is characteristic of the usual type of carburetor having a jet nozzle located in the center of the venturi, to give a rich mixture at high engine speeds. This is corrected in the present construction by admitting air into the fuel supply prior to its entrance through the annular and restricted discharge opening, and this arrangement also provides efficient means for regulating the amount of fuel at high engine speeds. 90 By limiting the amount of air which may enter the well through the orifice 9, the amount of fuel which will be consumed at various engine speeds, may be regulated, as for instance, should no air be permitted to enter the well, the fuel outlet at all speeds will be directly under the influence of the suction produced in the venturi, and by varying the amount of air entering the well, 95 the strength of the mixture may be controlled. 100

To provide for easy starting of the engine, a tubular choke member 26 having a closed and tapered upper end 27 is provided within a suitable bearing in the lower part 105 of the carburetor body and this choke member is moved vertically endwise by means of a link and lever connection, indicated at 28, to project its upper tapered end into the restricted portion of the venturi, further restricting the passage at the point where the main fuel outlet 17 opens into it, and thus the strong suction and higher air flow created thereby at the discharge will give a 110 strong mixture for starting purposes. 115

While the construction shown in the accompanying drawing has been described in detail, it will be understood that changes may be made therein without departing from the spirit of the invention, and I do not, therefore, limit myself to the particular construction or arrangement, except as specifically limited in certain of the appended claims. 120

Having thus fully described my invention, what I claim is:—

1. In a device of the character described having a main air passage, a Venturi restriction in said passage comprising an upper and a lower member inserted in the pas- 125

- sage with a restricted space between the adjacent end surfaces of said members to form an annular fuel outlet opening into the main air passage, said members together 5 forming an annular fuel chamber communicating with the outlet and one of said members having an annular flange extending into said annular chamber and providing a restriction between said outlet and chamber.
- 10 2. In a device of the character described having a main air passage, a Venturi restriction in said passage comprising an upper and a lower member, said lower member having an upwardly extending annular rib 15 with its upper face spaced from the adja-
- cent lower face of the upper member to provide a horizontally disposed annular outlet passage opening through the venturi into the main air passage, said annular rib also forming at the outer side thereof an annular 20 chamber surrounding the venturi, and an annular flange on the upper member extending downward into the annular chamber and spaced a restricted distance from the outer vertical face of said rib on the lower 25 member to provide a restriction between the annular chamber and the annular outlet passage.

WALTER MORTON.
